CLAIM

The ornamental design for a merchandising display channel front, as shown and described.

DESCRIPTION

FIG. 1 is a perspective view of a merchandising display channel front showing our new design;

FIG. 2 is a front elevation thereof;

FIG. 3 is a right side elevation thereof; the left side elevation being a mirror image thereof;

FIG. 4 is a top plan view thereof; and,

FIG. 5 is a bottom plan view thereof.

The broken lines showing the channel body are for illustrative purposes only and form no part of the claimed design. The broken lines which define the boundaries of the merchandising display channel front form no part thereof.
